A. OLEVIN

THIMBLE

Filed Nov. 22, 1922

ADOLPH OLEVIN

By *Thos. J. Donnelly*
Attorney

UNITED STATES PATENT OFFICE.

ADOLPH OLEVIN, OF HIGHLAND PARK, MICHIGAN.

THIMBLE.

Application filed November 22, 1922. Serial No. 602,496.

My invention relates to a new and useful improvement in a thimble and has for its object the provision in a thimble of means for severing the thread used in sewing.

Another object of the invention is the provision in a thimble of a cutting member adapted for movement into and out of operative position.

Another object of the invention is the provision of a thimble having a cutting member mounted thereon and provided with a guide member for permitting the movement of said cutting member into operative position and for shielding the same when moved to inoperative position.

Other objects will appear hereinafter.

The invention consists in the arrangements and combinations of parts hereinafter described and claimed.

The invention will be best understood from a reference to the accompanying drawings which form a part of this specification and in which,

Fig. 1 is a side elevational view of the invention,

Fig. 2 is a sectional view taken on substantially line 2—2 of Fig. 1.

Fig. 3 is a perspective view of the knife used in the invention,

Fig. 4 is a side elevational view of a thimble having a modified form of the invention shown in section,

Fig. 5 is a sectional view taken on substantially line 5—5 of Fig. 4,

Fig. 6 is a top plan view of a further modified form,

Fig. 7 is a sectional view taken on substantially line 7—7 of Fig. 6,

Fig. 8 is a top plan view of the form shown in Fig. 1, and

Fig. 9 is a side elevational view of the invention with the cutting member removed.

The invention is adapted for use with thimbles used by tailors, seamstresses and the like in hand sewing for facilitating the passage of the needle through the fabric worked upon. After the proper amount of sewing has been done and it is desired to sever the thread so as to release the needle from the fabric the operator either bites the thread or uses a pair of scissors or a detached knife to cut the thread. Often the scissors or knife has been mislaid so that a loss of time results. A biting of the thread will soon result in injury to the teeth. To provide means which will be

present with the thimble at all times for the severing of the thread an attachment on the thimble is present.

The invention in its preferred form comprises a knife blade or cutting element mounted on the thimble 12 which is provided at its open end with the usual bead 15. Punched out of the thimble, and extending lengthwise thereof, are guide members 13 and 14, the lower end of which is separated from the main body of the thimble and the upper end thereof is merely raised up from the thimble sufficiently to provide a passage way for the cutting member 17, so that the passage formed by the guide members 13 and 14 is open at the end adjacent the open end of the thimble and closed at the opposite end so as to limit the movement of the cutting member in said passages. The knife 17 is wider at its base than at its point so as to provide a shoulder 16. The knife blade is positioned in the passages formed by the members 13 and 14, the wide end thereof being so positioned that when the blade is moved to the operative position, shown in dotted lines in Fig. 1, the shoulder 16 will engage the closed end of the passage and its movement thereby limited, the knife blade being adapted for slidable movement in said passages. The blade is provided adjacent its butt end with a raised portion or rib 18 which may be engaged by the finger nail for imparting slidable movement to the blade.

The knife blade is provided with a cutting edge 18" having a beveled side 18' which inclines toward the back of the knife so as to provide a cutting edge sharpened on only one side. It has been found from experience that a blade having only one side sharpened is more efficient when used by the seamstress for ripping purposes, as it will not cut the fabric on the under side of the blade. The portion 21 of the thimble lying between the guides forms the backing surface along which the blade is adapted to slide.

In the form shown in Fig. 6 and Fig. 7 the top 22 of the thimble is provided with a recess stamped therein, to the side walls of said recess 23 is pivotally mounted adjacent its butt end a knife blade 24, a suitable rivet 25 being projected through said side walls. In this case the knife blade is raised to operative position in the same manner as the blade of a pocket knife.

- In the form shown in Figs. 4 and 5 a cup shaped cap 26 is provided which is adapted to fit tightly over the top end of the thimble. The cap is provided on its outer surface of the closed end with a recess 27 stamped therein having side walls 28 through which is projected a suitable rivet 25 for pivotally mounting the knife blade 24' therein.
- 10 The thimble may be made from any desirable material which will serve the purposes and when it is desired to sever the thread used in sewing the cutting member is moved to operative position and when the 15 cutting operation is over it is again moved to inoperative position so that the thimble to all intents and purposes serves the purpose of the ordinary thimble.

I am aware that various modifications and 20 changes may be made in the specific structure of the thimble but I do not wish to limit myself to the precise forms of structure shown but desire to avail myself of such variations and modifications as come within 25 the scope of the appended claims.

Having thus described my invention what I claim as new and desire to secure by Letters Patent is:

1. A thimble of the class described comprising a main body portion having channel formed guide members punched therefrom and provided with an integral rib projecting between said guide members, said rib lying in its original position and said 35 guide members being pressed outwardly of the periphery of the main body of said

thimble; a cutting element slidably mounted in said channels, said cutting element having a recess formed on the inner side thereof; and an abutment member punched 40 from said rib and adapted for engagement in said recess upon the movement of said cutting element to a predetermined position.

2. A thimble of the class described comprising a main body portion having struck 45 therefrom oppositely disposed channel shaped guide members pressed outwardly from the periphery of said main body portion; a central rib extending medially of said channel shaped guide members and 50 formed integral with said main body portion; and a cutting element slidably positioned in said guide members and adapted for slidable engagement with said rib.

3. A thimble of the class described comprising a main body portion having oppositely disposed channel shaped guide members struck therefrom pressed outwardly from the periphery thereof; a rib integral 55 with said main body portion and extending intermediate said guide members; a shoulder formed on the outer surface of said rib; a cutting element mounted slidably between said guide members and provided with a recess for the reception of said shoulder 60 upon movement into registration therewith for locking said cutting element against slidable movement.

In testimony whereof I have signed the foregoing specification at Detroit, in the 70 county of Wayne and State of Michigan.

ADOLPH OLEVIN.
